DRAFTING APPARATUS

William Henry Murphy, Chicago, Ill., assignor,
by mesne assignments, to Engineering Manufacturing Co., Sheboygan, Wis., a corporation
of Wisconsin

Application September 25, 1944, Serial No. 555,609

3 Claims. (Cl. 33—80)

1

This invention relates to improvements in drafting apparatus.

One object of the invention is to provide a movable or mobile parallel straight-edge construction that facilitates adjustment of a drafting blade thereof into or out of parallelism with a selected base line, for example.

Another object of the invention is to provide improvements that enable adjustment of a straight edge relative to parallel-guiding means of drafting apparatus, whereby the straight edge can be indexed or adjusted readily with respect to a selected base line of a drawing, thereby avoiding the frequently more troublesome task involved in adjusting such a line of a drawing into registration with the straight edge of such drafting apparatus.

An additional object of the invention is to provide means for effecting a fine angular adjustment of a guided straight edge of drafting apparatus, said adjusting means having an angle indicating scale or the like associated therewith, if desired.

Other objects of the invention relate to various features of construction and arrangement of parts which will be apparent from a consideration of the following specification and accompanying drawings wherein.

Figure 1 is a top plan view of drafting apparatus including a drafting board or table and guided straight edge embodying adjusting means that are illustrative of the present invention.

Fig. 2 is an enlarged broken top plan view of an end portion of the straight edge and associated adjusting means shown in Fig. 1;

Fig. 3 is a side elevation of the structure shown in Fig. 2;

Fig. 4 is a broken top plan view of a straight edge provided with a modified form of adjusting means;

Fig. 5 is a view similar to Fig. 4 but showing the straight edge in an exaggerated position of angular adjustment relative to the associated guiding means;

Fig. 6 is a sectional view taken on line 6—6 of Fig. 4;

Fig. 7 is a top plan view of an end portion of a straight edge and associated carriage provided with means for effecting fine angular adjustments of the straight edge.

Referring to the drawings, numeral 10 indicates generally, a conventional drafting board or table, over the upper surface of which a straight edge 11 is adapted to be guided into successive parallel positions by means of conventional guiding ap-

2

paratus. The guiding means shown comprises a cable 12 which passes around pulleys 15, 16 at the lower edge of the board, and pulleys 17, 18 adjacent the upper edge. The cable 12 is secured to carriages indicated generally by the numerals 19, to which carriages the ends of the straight edge 11 are attached. The cable referred to and the pulleys are mounted on the lower surface of the drafting board while the carriages or brackets 19 are disposed at opposite side edges of the board and serve to maintain the straight edge in a position constantly parallel with a given line as the straight edge is moved forwardly or rearwardly over the surface of the board or rather, over the surface of a drawing sheet attached to the board. In Fig. 1 of the drawing a conventional slack adjuster 20 is shown for tensioning cable 12.

As viewed in Figs. 2 and 3, each carriage 19 is in the form of a metal bracket, having a lower inwardly directed flange 21, which constitutes a clip within which the cable 12 is firmly clamped against slippage. The vertical portions 22 of the carriages 19 project upwardly along the parallel side edges of the drafting board 10 and each spans between or connects one of the flanges 21 with an upper inwardly turned flange 23. The ends of the straight edge are attached to opposed flanges 23 at opposite margins of the board 10.

The means for attaching the straight edge to the flanges 23 of the carriages are, in accordance with the present invention, of such character as to provide for angular adjustment of the straight edge as distinguished from attaching means commonly employed which retain the straight edge in a relatively fixed position of parallelism with respect to a given line. The attaching means shown in Figs. 1, 2, and 3, best illustrated in Figs. 2 and 3, comprises a stud 24 secured at each end of the straight edge and received within a threaded recess in a thumb nut 25. The stud shown in Figs. 2 and 3 passes upwardly through an arcuate slot 26 provided in the respective flange 23. The radius upon which the slot 26 is generated, corresponds generally to the distance between the two studs 24 or, generally, to the width of the drafting board or the length of the straight edge. By reason of the construction described the straight edge can be adjusted angularly upon the carriages, the carriages remaining attached to the cable 12. Such adjustment of the straight edge with respect to the carriages, or with respect to a given line can be effected by loosening the nut 25 at the right hand end in Fig. 1 and slightly loosening the opposite nut 25 also. The straight edge 11 can then be swung angu-

larly about the left hand stud as a pivot from the full line to the dotted line position shown in Fig. 1. The range of angular adjustment in swinging about one stud as a pivot is limited by the length of the slot at the swinging end of the straight edge, but such range is increased by the provision of two such slots, one in each carriage, as will be obvious. However, it will be understood that but one slot need be employed in utilizing the principle of the present improvements, since instead of a slot in one of the brackets, a cylindrical opening only may be employed for receiving the corresponding stud as a pivot.

With the improvements described, a draftsman, after mounting a drawing on the board with a given base line approximately parallel to the straight edge, can readily adjust the straight edge into precise parallelism with said line and thereafter, during movement of the straight edge across the face of the board, the straight edge maintains parallelism with said line. Such arrangement is a substantial convenience where drawings are placed upon a drafting board for additions or for corrections, since generally it is simpler to make a precise adjustment of the straight edge with respect to a given line on a drawing than to adjust a drawing with respect to the straight edge and thereafter attach the drawing to the board to obtain the same relative positioning.

A modified structure illustrative of the invention is shown in Figs. 4 to 6 inclusive. In Fig. 6 a carriage for a straight edge is indicated generally by the numeral 27 and is shown with the lower flange 28, to which a cable 12, similar to the above described cable, and located at the rear of board 10, is similarly attached. The carriage 27 is provided with an upper flange 29 shown as overlying the adjacent upper marginal portion of the board. The adjacent end of the straight edge 30 is pivotally attached, by means of a pin 31, to a disc or other member 32 which carries a stud 33, about which the disc is pivotally movable through a limited arc. The stud 33 extends upwardly through an aperture 34 in the flange 29 and is provided at its upper threaded end with a clamp nut 35. Upon loosening the nut 35, the disc 32 is free for limited swinging movement about the stud 31 as a pivot and hence the adjacent edge of the straight edge 30, being pivotally attached by pin 31 to an off-center portion of the disc, can be swung arcuately or adjusted angularly, about a pivotal connection with a second carriage at the other end of the straight edge. Such pivotal movement may of course be afforded by a carriage and clamp construction similar to the structure shown in Fig. 6. Where a carriage construction similar to that shown in Fig. 6 is employed at each end of the straight edge, small angular adjustment of the latter can be effected by loosening only the nut 35 at the end of the straight edge that is to be swung. At the opposite end, the pin 31 forms a pivot about which the straight edge swings as it is being adjusted into a selected angular position, although angular adjustments in opposite directions may be made at both ends of the straight edge if required.

The modification illustrated in Fig. 7 is generally similar to that shown in Figs. 1 to 3 inclusive and comprises a carriage 36 provided with an arcuate slot 37 within which a stud 38 carried by the adjacent end of a straight edge 11 may be moved. On the upper surface of the carriage 36 is an internally threaded member 39

having a flat apertured end through which the stud 38 passes. An upturned flange 40, shown integral with the carriage 36, has an aperture through which loosely passes an adjusting screw 41, which is received within the threaded barrel portion 42 of the member 39. Stops 43 are shown secured to the screw shank on adjacent sides of the flange 40 to prevent longitudinal movement of the screw with respect to the flange. The outer end of the screw 41 is provided with the small knob 44 for convenience in rotating the screw whereby, when clamp nut 45 carried by the stud 38 has been loosened, rotation of the screw 41 will effect adjustment of the stud 38 along the slot 37 in one direction or the other, depending upon the direction of rotation of the screw. Such movement of the stud 38 effects angular adjustment of the straight edge as in the above described modifications of the invention, but by means of the screw adjustment shown in Fig. 7 a very fine or micrometric angular adjustment of the straight edge can be effected readily.

While a clamp nut 45 is shown in Fig. 7, similar to the corresponding elements shown in the preceding figures, it will be apparent that after making an adjustment of the straight edge by rotation of the screw 41, it is not essential that the nut 45 be turned down to effect a clamping action of the corresponding end of the straight edge to the carriage as in the preceding described structure, since the adjusting screw 41 will retain the straight edge in the adjusted relation. However, the use of the clamp nut 45 is preferred.

In Fig. 7 a scale 46 is shown on the upper surface of the carriage 36 and associated with the scale is a pointer 47 attached to or integral with the end of member 39 which pointer moves with the adjacent end of the straight edge when the same is being adjusted by operation of the screw 41. The graduations of the scale preferably indicate degrees of arc or fractions thereof, and deviation of the pointer 47 from the central zero point 48 indicates the extent of angular adjustment of the straight edge to one side or the other of a given base line.

While structures illustrative of the invention have been shown and described, it will be apparent that variations of such structures may be utilized within the spirit of the invention and the scope of the appended claims.

I claim:

1. In combination, a drafting board, movable members comprising separate carriages mounted for reciprocable but nonpivotable movement in unison along opposed portions of the board for guiding a straight edge over the drafting surface of the board into successive parallel positions, said carriages comprising flanges provided with arcuate slots therein, and releasable means for clamping each end of the straight edge to one of said flanges comprising movable members movably adjustable within the respective slots for varying the angular relationship of the straight edge with respect to a given line.

2. In combination, a drafting board, movable members comprising independent carriages mounted for reciprocable but nonpivotable movement in unison along opposed portions of the board for guiding a straight edge over the drafting surface of the board into successive parallel positions, said carriages comprising flanges provided with arcuate slots generated therein about a radius corresponding in length

to the distance between the slots, and releasable clamping means at each end of the straight edge releasably clamping the same to one of said flanges, said means each comprising a movable threaded member which can be adjustably positioned within the respective slot for varying the angular relationship of the straight edge with respect to a given line.

3. In combination, a drafting board, movable guiding means for a straight edge, arcuately slotted separate carriages secured to said guiding means and movable thereby in unison along opposed portions of the board for guiding a straight edge over the drafting surface of the board into successive parallel positions, said carriages being mounted for reciprocable but not pivotable movement along said board, a straight edge, and means securing the ends of the straight edge to said carriages and comprising threaded clamping members having portions operable within the arcuate slots of said

carriages for varying the angular position of the straight edge with respect to a given line.
